TEARABLE BLISTER PACKAGE

Eugene J. Meierhoefer, 48 Bald Eagle Road,
Panther Valley, Hackettstown, N.J. 07840

Filed Sept. 28, 1973, Ser. No. 401,753

Term of patent 14 years

Int. Cl. D9—05

U.S. Cl. D9—192

FIG. 1 is a perspective view of a tearable blister package showing my new design;

FIG. 2 is a top plan view thereof;

FIG. 3 is a right side elevational view;

FIG. 4 is a front end elevational view;

FIG. 5 is a rear end elevational view;

FIG. 6 is a top plan view of a tearable blister package showing a modified form of my new design.

The bottoms of both embodiments are plain and unornamented save for the two slits extending inwardly from the outer perimeter as seen in FIGS. 2 and 6.

I claim:

The ornamental design for a tearable blister package, substantially as shown and described.
